NO. 14,562

JAN 22, 1884

UNITED STATES PATENT OFFICE.

SARAH JANE SHIELS, OF NEW YORK, N. Y., ASSIGNOR TO THE BUTTERICK PUBLISHING COMPANY, (LIMITED,) OF SAME PLACE.

DESIGN FOR A LADY'S WALKING-SKIRT.

SPECIFICATION forming part of Design No. 14,562, dated January 22, 1884.

Application filed November 19, 1883. Term of patent 3½ years.

To all whom it may concern:

Be it known that I, SARAH JANE SHIELS, of the city, county, and State of New York, have invented and produced a new and original Design for a Pattern of a Lady's Walking-Skirt, (numbered 8,961;) and I do hereby declare that the engraved prints accompanying this specification convey to any one accustomed to using paper patterns a clear understanding of how a garment made up by the pattern will appear.

The design shows a walking-skirt combined with draperies. There is a short drapery at the right side that displays draping plaits in its front and back edges, droops over a long

panel drapery, and joins a deep left-side drapery that exhibits draping plaits in its back edge. The deep, full back drapery exhibits draping plaits in its front edges and loopings in the center.

What I claim as my invention, and desire to secure by Letters Patent, is—

The design for a lady's walking-skirt, as shown in the engraved prints accompanying this specification.

SARAH JANE SHIELS.
